UNITED STATES PATENT OFFICE.

HENRY CAMPBELL, OF LIBERAL, KANSAS.

AUTO CHAIN COUPLER.

Application filed December 15, 1921. Serial No. 522,606.

To all whom it may concern:

Be it known that I, HENRY CAMPBELL, a citizen of the United States, residing at Liberal, in the county of Seward and State of Kansas, have invented a new and useful Auto Chain Coupler, of which the following is a specification.

This invention relates to connecting links for chains, and more particularly to a connecting link designed for use in connection with anti-skid chains or the like, the primary object of the invention being to provide a link having novel means to lock the link section associated therewith, against movement.

Another object of the invention is to provide a link of this character wherein the movable element thereof is guarded against contact with obstructions encountered on a road surface to eliminate any possibility of the movable element being accidentally moved to uncouple the chain.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view of a link constructed in accordance with the present invention showing the same as connected to links of a chain.

Figure 2 is a side elevational view of the detachable link, showing one of the side members thereof as removed, and the removable element in a locked position.

Figure 3 is a plan view of the link.

Referring to the drawings in detail, the link includes side plates 5 which are held in spaced relation by means of the plate 6, the latter plate being secured to the side plates as by means of the rivets 7. The side plates 5 are cut away as at 8 which cut away portion extends from one of the side edges of the plates, terminating at a point substantially intermediate the widths of the plates, and extends laterally as at 9 to provide a hook member at one end of the plates to accommodate a link of a chain, the link being indicated at 10. The central or spacing plate 6, is formed with a cut out portion,

the walls thereof being cut away as at 11 to accommodate the movable element 12, which is in the form of a disk and is provided with a cut out portion 13 extending 60 from the edge thereof.

This movable element 12 is pivotally supported between the side plates 5 as by means of the pivot pin 14, to permit the movable element to rotate freely between the plates 65 to permit a link to be attached thereto. The plates are formed with openings indicated at 15, which accommodate the link 16, to secure the detachable link forming the subject matter of this invention, to one end of 70 a chain.

In the use of the connecting link, the movable element 12 is moved to a position as indicated by Figure 1 of the drawing, whereupon the link 10 may be positioned 75 in the cut out portion thereof. The movable element 12 is now rotated to move the same to a position as shown by Figure 1 of the drawing and permitting the link 10 to fall into the right angled portion of the cut out 80 portion of the link.

It follows that the movable element 12 is now rotated to bring one wall thereof to a position to close the right angled portion of the cut out portion of the plates, as shown 85 by Figure 2 of the drawing, whereupon the link 10 is locked against movement and may only be removed by manually rotating the element 12 to bring the cut out portion thereof into alignment with the link 10, 90 whereupon the movable element 12 may be rotated to release the link.

From the foregoing it will be seen that the movable element 12 is protected in every respect against accidental movement, due to 95 its contact with stones or other foreign matter, which a link of this kind may engage, on a road surface.

It will therefore be seen that the centrifugal motion of the rotating wheel will tend 100 to hold the disk to its closed position.

Having thus described the invention, what is claimed as new is:

A connecting link comprising side plates, a central plate conforming to the contour 105 of the side plates and positioned between the side plates, said plates having cut out portions extending from one of the respective edges thereof towards the central portions of the plates and having right angled portions, one of the walls of the right angled portions extending in parallel relation with

one of the edges of the plates, the central plate having a curved cut out portion merging with the first mentioned cut out portions, a movable element positioned in the 5 curved cut out portion and pivotally supported therein, said movable element having a cut out portion extending from one edge to align with the cut out portion of the plates and receive a link member, said movable member adapted to deliver a link to the 10

cut out portion of the plates, and said movable member adapted to close the cut out portions to lock the link therein.

In testimony that I claim the foregoing as my own, I have hereto affixed my signature in the presence of two witnesses.

HENRY CAMPBELL, M. D.
